Primary Examiner — Mary Ann Calabrese*Assistant Examiner* — Sloan Rozin(74) *Attorney, Agent, or Firm* — TraskBritt(57) **CLAIM**

The ornamental design for a pocket holder for a music stand, as shown and described.

DESCRIPTION

FIG. 1 is a perspective view of a pocket holder for a music stand;

FIG. 2 is a front elevation view of the pocket holder shown in FIG. 1;

FIG. 3 is a rear elevation view of the pocket holder shown in FIG. 1;

FIG. 4 is a top plan view of the pocket holder shown in FIG. 1;

FIG. 5 is a bottom plan view of the pocket holder shown in FIG. 1;

FIG. 6 is a left side elevation view of the pocket holder shown in FIG. 1;

FIG. 7 is a right side elevation view of the pocket holder shown in FIG. 1; and,

FIG. FIG. 8 is a perspective view of the attached pocket holder shown in FIG. 1.

The evenly spaced broken lines are directed to environment and form no part of the claimed design.
